US00D947979S

(12) **United States Design Patent** (10) Patent No.: **US D947,979 S**
(45) Date of Patent: **** Apr. 5, 2022**

(54) **ELECTRICAL CONTACT STRIP FOR A POWERED RAIL**

(71) Applicant: **T-Worx Holdings, LLC**, Sterling, VA (US)

(72) Inventors: **Eric F. Cabahug**, Fairfax, VA (US); **Tyler J. Miller**, Dickerson, MD (US); **Tho N. Ngyuen**, Ashburn, VA (US); **Benjamin F. Feldman**, Reston, VA (US)

(73) Assignee: **T-Worx Holdings, LLC**, Sterling, VA (US)

(**) Term: **15 Years**

(21) Appl. No.: **29/709,037**

(22) Filed: **Oct. 10, 2019**

(51) LOC (13) Cl. **22-01**

(52) U.S. Cl.

USPC **D22/108**

(57) **CLAIM**

The ornamental design for an electrical contact strip for a powered rail, as shown and described.

DESCRIPTION

FIG. 1 is an isometric view of the electrical contact strip for a powered rail shown on a firearm;

FIG. 2 is a right isometric view thereof separate from the firearm;

FIG. 3 is a left isometric view thereof;

FIG. 4 is a right side view thereof;

FIG. 5 is a left side view thereof;

FIG. 6 is a top view thereof;

FIG. 7 is a bottom view thereof;

FIG. 8 is a front view of thereof; and,

FIG. 9 is a rear view of thereof.

The evenly spaced dashed line showing of a firearm represents an exemplary environment and forms no part of the claimed design.

1 Claim, 5 Drawing Sheets
